CLAIM

The ornamental design for a stand alone torchiere lamp having task light on multi adjustable arm and tray, as shown and described.

DESCRIPTION

FIG. 1 is a side view of the torchiere lamp having task light or multi adjustable arm and a tray (the opposite side view is a mirror image thereof);

FIG. 2 is a front view thereof;

FIG. 3 is a rear view thereof;

FIG. 4 is a top view thereof;

FIG. 5 is a bottom view thereof; and,

FIG. 6 is a fragmented portion thereof showing the task light in an alternate position.
